UNITED STATES PATENT OFFICE.

HERBERT E. WALKER, OF CHICAGO, ILLINOIS.

STORAGE-BATTERY CLIP.

Application filed May 10, 1921. Serial No. 468,463.

To all whom it may concern:

Be it known that I, HERBERT E. WALKER, a citizen of the United States, and a resident of Chicago, in the county of Cook and 5 State of Illinois, have invented certain new and useful Improvements in Storage-Battery Clips; and I do hereby declare that the following is a full, clear, and exact description thereof, reference being had to the accompanying drawings, and to the characters 10 of reference marked thereon, which form a part of this specification.

This invention relates to improvements in battery clips of that general type shown 15 in my prior application for U. S. Letters Patent, Serial No. 359,578, filed February 18, 1920, and refers more specifically to the construction of the block or head to which is attached the members of the clip that 20 carry the jaws, and to means for forming on the block the terminal member by which the supply conductor is connected to the clip.

One of the objects of the invention is to simplify the manufacture of the block to 25 which the jaw members are attached, to reduce the cost of assembling the elements of the clip, to reduce the amount of metal required to form the block, and to improve the appearance of the clip.

30 A further object of the invention is to produce a block for connecting together the jaw members, that is formed of open work construction to permit a free flow of air through and about the members of the block 35 so as to air cool the block and the adjacent ends of the jaw members and thereby prevent the same becoming unduly heated.

The invention consists in the arrangement and combination of the elements shown in 40 the drawings and described in the specification, and is pointed out in the appended claims.

In the drawings:

Figure 1 is a plan view of a storage battery clip provided with a block embodying my invention.

Figure 2 is a perspective view of said block.

As shown in the drawings, 10, 10 designate jaw members of the clip which are formed at their forward ends to provide jaws 11 for grasping the element of a storage battery to which the clip is attached, and are made plain at their rear ends, and 55 12 designates the block to which the rear plain ends of the jaw members are attached,

and which is shaped to form fulcrums about which the jaw members are caused to be flexed between their front ends and the portions of the jaw members which are attached 60 to said block. The construction of the jaws constitute in themselves no part of the present improvements, said improvements lying in the construction of the block by which to join the jaw members together, and the 65 construction of the terminal at said block through which the source of current supply is connected with the clip.

The said block and terminal are made of a single piece of sheet metal suitably formed 70 and swaged to give a general wedge shape to the block, with the blunt end of the wedge directed towards the jaws, and with one member of the block thus formed extending rearwardly beyond the converging ends of 75 the block members to constitute a terminal member.

Referring more specifically to the construction of the block, it comprises two converging members 14, 15, which are integrally connected at the wider front end of the block by a transverse connecting member 16 that constitutes the broad end of the wedge-like block. The upper and lower 80 faces of the converging members constitute 85 seats to receive the rear ends of the jaw members, which latter lie flat thereon, as shown in Figure 1, and may be attached to the block by a bolt or rivet 19 which extend through openings 17 and 18 of the block 90 members, and through openings in the ends of the jaw members.

In addition to the fastening means thus described, shoulder means are provided at the side margins of the converging members 95 14 and 15 to prevent lateral or swinging movement of the jaw members relatively to the block. Said shoulders are formed as integral parts of the side edges of the converging members of the block by turning 100 the marginal portions of said members upwardly and downwardly, respectively, in the operation of forming the block. Thus there is produced on each member parallel shoulder flanges 20. The rear ends of the jaw 105 members are made of a width to fit snugly between said shoulder flanges and thereby avoid twisting of the jaw members relatively to the block.

One of the block members, the member 14 as 110 herein shown, is continued rearwardly from the rear edge of said member to constitute an

integral terminal member 21 by which to connect a supply conductor to the clip. Said terminal member is part cylindric in cross section and is joined to the rear edge of the block member 14 from which it springs by a narrow neck portion 22. This construction of the terminal member permits the conductor to be readily attached to the terminal members by placing the conductor 10 within the hollow terminal member and thereafter pressing or pinching the free margins downwardly on the conductor. If desired, the neck portion 22 of the extension may be provided with an aperture 24 15 to receive parts of the conductor strands and solder by which the conductor can be more firmly attached to the terminal member.

From what has been said, it will be observed that the block can be made with a 20 minimum weight of metal, while at the same time producing an arch-like structure which greatly reinforces and strengthens the block, as a whole. It will also be noted that the block is of open work construction so 25 that air may pass freely therethrough to cool the block and to prevent the material of the block and the adjacent ends of the jaw members becoming unduly heated. A further advantage of the construction is 30 that the terminal member 21 can be formed on the block at the same time the strip of metal is bent and swaged to produce the block so as to thereby avoid an additional assembling step.

35 The structural details of the block may be somewhat varied within the spirit and scope of the claims hereto appended.

I claim as my invention:

40 1. A clip comprising two opposed resilient members and their jaws, of a block made of a single piece of sheet metal, said block embracing converging members to which the jaw members are attached, said converging members being joined at the front end of the block by an integral transverse member.

45 2. A clip comprising two opposed resilient members and their jaws, of a combined block and conductor terminal made of a single piece of sheet metal, said block embracing 50 converging members to which the jaw members are attached, and said converging members being formed at their side edges with integral jaw member limiting shoulders.

55 3. A clip comprising two opposed resilient members and their jaws, of a combined block and conductor terminal made of a single piece of sheet metal, said block embracing converging members to which the jaw members are attached, said converging members

being joined at the front end of the block 60 by an integral transverse member, and said converging members being formed at their side edges with integral jaw member limiting shoulders.

4. In a clip for the purpose set forth, a 65 block made of a single piece of sheet metal, embracing a front transverse and two rearwardly converging members, one of the converging members terminating beyond the block in a conductor terminal member. 70

5. In a clip for the purpose set forth, a block made of a single piece of sheet metal, embracing a front transverse and two rearwardly converging members, said converging members being provided with registering 75 openings to receive attaching means to fasten jaw members of a clip on the block.

6. In a clip for the purpose set forth, a block made of a single piece of sheet metal, in the form of an open wedge, with the wide 80 end of the wedge facing forwardly and provided at the sides of its converging faces with integral raised flanges constituting stop shoulders.

7. In a clip for the purpose set forth, a 85 block made of a single piece of sheet metal, in the form of an open wedge, with the wide end of the wedge facing forwardly, one of the converging members of the block terminating in an integral rearwardly extending 90 conductor clip member.

8. In a device of the class described, a pair of spring jaw members having substantially straight shanks set at an acute angle to each other and a sheet metal connecting member lying between the ends of said shanks for holding them rigidly in co-operating relation, said member having an integral lug for connection to an electrical conductor. 95

9. In a device of the class described, a pair of jaw members having substantially straight spring shanks set at an acute angle to each other, and an integral sheet metal connecting member having two sides lying 100 in contact with the sides of said shanks, a base member forming a strip between the said sides, one of said sides being extended and formed into a channeled lug for the reception of an electric conductor and a rivet 105 passing through the ends of said shanks and through the sides of said connecting member to draw the same securely together.

In witness whereof I claim the foregoing as my invention, I hereunto append my signature this 9th day of May, 1921. 115

HERBERT E. WALKER.
